UNITED STATES PATENT OFFICE.

SAMUEL GUTERMAN, OF NEW YORK, N. Y.

CONVERTIBLE FURNITURE.

Application filed March 20, 1925. Serial No. 17,103.

To all whom it may concern:

Be it known that I, SAMUEL GUTERMAN, a citizen of Brazil, and resident of the city of New York, in the county of Bronx and 5 State of New York, have invented certain new and useful Improvements in Convertible Furniture, of which the following is a specification.

The present invention relates to improvements in convertible furniture, and has for 10 its main object to provide an article of that character which may serve at one time as a chair for infants, differing little in appearance from ordinary forms of chairs, 15 and which may be conveniently converted into a baby carriage.

With these and other objects in view, which will more fully appear as the nature 20 of the invention is better understood, the same consists in the combination, arrangement and construction of parts hereinafter described, pointed out in the appended claims and illustrated in the accompanying drawings, it being understood that many 25 changes may be made in the size and proportion of the several parts and details of construction within the scope of the appended claims, without departing from the spirit or sacrificing any of the advantages 30 of the invention.

One of the many possible embodiments of the invention is illustrated in the accompanying drawings, in which:

Figure 1 is a side elevation of the improved convertible chair and baby carriage with the parts arranged for use as a chair; Fig. 2 is a front elevation thereof; Fig. 3 is a side elevation of the same with the parts folded for transportation or storage; and 40 Fig. 4 is a side elevation of the article showing the device arranged for use as a baby carriage.

The convertible furniture comprises a supporting frame, including two pairs of 45 spaced apart side members, each pair consisting of two bars 10 and 11, which are crossed and pivotally connected together by means of a rod 12, which extends from one of said side members to the other. The 50 upper ends of the bars 10 are connected by a transverse rail 13, while upon the upper portions of the bars 11 is formed a chair back 14. The bars 10 and 11 carry adjacent their lower ends wheels 15 and 16, respectively, which are in contact with the floor

when the chair is converted into a crib, as clearly shown in Fig. 4 of the drawings, but are out of contact with the floor when the furniture is in the form of a chair, as 60 shown in Fig. 1. To each of the bars 11 is pivoted at 17, adjacent the chair back 14, an arm rest 18, connected by a transverse table portion 19, which is adapted 65 to rest upon the upper ends of the supporting bars 10 and upon the transverse rail 13. For the purpose of keeping the table portion in position upon the rail 13, the latter and the said table portion are provided with coacting fastening devices of any suitable construction. For instance, 70 the table portion is provided with two or more hooks 20, adapted to engage pins 21 on the transverse rail 13 (Figs. 1 and 2).

To the bars 10 is pivoted at 22, above the pivot rod 12, a foot rest 23, that is adapted 75 to be held in substantially horizontal position by links 24, which are pivoted at 25 to the bars 10. The outer ends of the foot rest and links 24 carry coacting fastening 80 devices, by means of which the foot rest is held in its extended position (Fig. 1). These fastening devices may be of any suitable construction. In the case illustrated, the links 24 carry hooks 26, engaging 85 with pins 27 on the foot rest. The foot rest is also provided with a row of pins 28, similar to the pins 21 on the rail 13, for a purpose hereinafter to be described. When the chair is converted into a baby 90 carriage, the foot rest 23 and the links 24 are folded up against the bars 10. In order to hold the elements in these positions (Fig. 4), catches 29 are mounted on the bars 10, engaging the foot rest.

The combined chair seat and bed bottom 95 is in the form of a web 30, of any suitable fabric. This web is attached to the chair back 14, its width corresponding to the distance between the side members, constituted by the two pairs of bars 10 and 11. 100 When the furniture is in the form of a chair, the web is carried around a tie-rod 31, connecting the bars 10 above the pivots 25 of the links 24, and is thence passed downwards and below the foot rest 23, its free end being provided with apertures through which the pins 28 on the outer end of the foot rest may be extended. 105 When the chair is converted into a baby carriage, the free end of the web is dis- 110

engaged from the pins on the foot rest and engaged with the pins 21 on the transverse rail 13.

In order to hold the bars 10 and 11 in the positions shown in Fig. 4 of the drawings, each of the bars 11 carries a link 32, having a hook-shaped free end 33, that is adapted to be engaged with pins 34 on the bars 10.

10 Each pair of bars 10 and 11 is connected by a side rail 35, in the form of a lazy-tong construction, the same being disposed above the pivot rod 12 and forming side rails both for the chair and the baby carriage. On 15 each lazy-tong construction the free end of the outermost link has pivoted to it a longer link, denoted by the numeral 36, which may be secured to one of the arm rests 18 when the latter are swung back to 20 form a continuation of the chair back 14, as clearly shown in Fig. 4 of the drawings. The said arm rests and the elements carried thereby are thus held in their extended positions. To the arm rests 18 and the table 25 portion 19 is fastened in any suitable manner a canopy 37, the outer end of which is fastened in any suitable manner to a U-shaped frame 38, which is pivoted at 39 to the arm rests 18. The canopy is adapted 30 to be folded against the arm rests 18 and the table portion 19 when the furniture is to be used as a chair, and is adapted to be extended, as shown in Fig. 4 of the drawings, when the chair is converted into a baby 35 carriage. In order to hold the canopy in its extended position, a cord 40 is connected to the frame 38, the free end of the said cord being adapted to be brought into engagement 40 with one of the pins 21 on the rail 13 (Fig. 4).

From the foregoing and by reference to the drawings it will be clearly seen that the furniture may be readily folded for transportation or storage by swinging the arm 45 rests 18 and table portion 19 against the bars 11 and then causing the bars 10 to swing against the bars 11, whereby the side rails 35 are automatically folded, the elements being then in the positions shown in 50 Fig. 3 of the drawings, from which it appears that the furniture rests on the bars 10 and 11, the wheels 15 and 16 being disposed at a distance from the lower ends of the said bars that prevents the said wheels 55 from coming into contact with the floor when the bars 10 and 11 are folded in the manner indicated. If it is intended to extend the furniture to form a chair, the bars 10 and 11 are swung away from one another into the 60 positions shown in Fig. 1 of the drawings and the arm rests 18 and table portion 19 swung into horizontal position so that the table portion 19 rests on the top of the bars 10, the coacting hooks 20 and pins 21 being

brought into engagement to hold the elements in the positions indicated. The foot rest 23 is then brought into horizontal position and the links 24 engaged therewith, and finally the web 30 fastened to the foot rest. In order to convert the chair into a 70 baby carriage, first the web 30 is disengaged from the foot rest, and the latter together with the links 34 folded against the bars 10, the catches 29 being engaged with the foot rest. After this, the arm rests 18 and 75 table portion 19 are swung back to form a continuation of the chair back, and the bars 10 and 11 swung apart until they rest on the wheels 15 and 16, respectively. The links 32 are then engaged with the pins 34, and the links 36 with the arm rests 18. Thereafter the web 30 is engaged with the pins 21 on the rail 13 and the canopy 37 extended, it being held in extended position by bringing the free end of the cord 40 into 80 engagement with one of the pins 21. It is to be observed that, when the elements are in the positions shown in Fig. 1 of the drawings, the wheels 15 and 16 do not rest on the floor, whereby the chair is securely held 90 against movement.

What I claim is:—

1. A convertible chair and baby carriage comprising a supporting frame including a pair of spaced apart side members pivotally and transversely connected together between their ends, each of said members consisting of two bars crossed at their pivots, a chair back carried by one pair of said bars, arm rests pivoted to said last mentioned pair of bars adjacent said chair back, a transversely extending table portion connecting said arm rests, said arm rests and table portion being adapted to rest upon the other pair of said bars or to form an extension of said chair back, a web secured to said chair back, a foot rest carried by that pair of said supporting bars upon which said arm rests and table portion are adapted to rest, the free end of said web being adapted to be secured to said foot rest to form a chair seat or to the upper ends of those supporting bars to which said foot rest is attached when said supporting bars are extended to form a baby carriage, whereby said web constitutes a bed bottom.

2. A convertible chair and baby carriage according to claim 1, comprising side members in the form of lazy-tong constructions secured to said supporting bars, and means carried by said lazy-tong constructions for holding said arm rests and table portion in the plane of said chair back.

Signed at New York, in the county of New York, and State of New York, this 11th day of October A. D. 1924.

SAMUEL GUTERMAN.
